US00D797425S

(12) **United States Design Patent** (10) **Patent No.:** **US D797,425 S**
Wegener (45) **Date of Patent:** **** Sep. 19, 2017**

(54) **GRIPPING SOLE FOR FOOTWEAR**

(71) Applicant: **Bunzl Brands & Operations Pty Limited**, Erskine Park, NSW (AU)

(72) Inventor: **Caleb Wegener**, Beecroft (AU)

(73) Assignee: **BUNZL BRANDS & OPERATIONS PTY LIMITED**, Erskine Park NSW (AU)

(**) Term: **15 Years**

(21) Appl. No.: **29/570,325**

(22) Filed: **Jul. 7, 2016**

(30) **Foreign Application Priority Data**

Jan. 8, 2016 (AU) 201610093
